UNITED STATES PATENT OFFICE

JAMES T. BARBER, OF BROOKLYN, NEW YORK

DRUM-WASHING MACHINE

Application filed November 23, 1927. Serial No. 235,389.

This invention relates to machines for cleaning containers, such as drums, barrels, casks and the like by a gyratory motion and is directed to the general structure and more particularly to the holding means for receiving the drums, and the operating mechanism for imparting the gyratory movement to the container during the washing or cleaning thereof.

10 While the drawing illustrates a preferred embodiment of the invention, it is to be understood that in adapting the means to meet specific needs and requirements the design may be varied and changes in the minor 15 details of construction may be resorted to within the scope of the invention as claimed, without departing from the spirit thereof.

For a full understanding of the invention and the merits thereof reference is to be had 20 to the following description and the drawings hereto attached, in which,

Figure 1 is a front view of a drum cleaning machine embodying the invention.

Figure 2 is an enlarged detail sectional view showing more clearly the means for mounting the drum holder and imparting a 25 gyratory movement thereto.

Figure 3 is an enlarged sectional view of the holder on the line 3—3 of Figure 1, looking 30 in the direction of the arrows.

Figure 4 is a detail sectional view of the holder on the line 4—4 of Figure 1, looking in the direction of the arrows.

Corresponding and like parts are referred 35 to in the following description and designated in the several views of the drawing by like reference characters.

The supporting frame of the machine comprises a base 1 and standards 2, 3 and 4. A 40 depression 5 is formed in the top side of the base 1 to receive and hold a quantity of water as well as to catch drippings when the machine is in operation. A shaft 6 is mounted in the standards 2 and 3 and has a belt pulley 45 7 fast thereto to receive motion from a suitable source of power by means of a drive belt, not shown, in a manner well understood. A gear wheel 8 is mounted in line with the shaft 6 and is secured to the standard 3 by means 50 of a brace 9. The shaft 6 passes loosely

through the gear wheel 8. A shaft 10 is loosely mounted in the standard 4 in line with the shaft 6. An eccentric 11 fast to the shaft 10 cooperates with an eccentric strap 12, which is connected by means of a rod 13 55 with the plunger rod of a pump 14 which pumps the water from the depression 5 and delivers it at the desired point of discharge.

The holder for the container, such as a 60 drum, barrel, or cask 15 consists of an outer frame 16 and an inner frame 17, and these frames may be of similar or like formation and usually consist of bars arranged in rectangular form and riveted or otherwise secured at the abutting points. Similar 65 sockets 18 and 19 are attached to diagonally opposite corner portions of the outer frame 16 and receive the inwardly facing ends of the respective shafts 6 and 10 which are secured thereto. The holder is diagonally 70 mounted and rotates about an axis having a diagonal arrangement. A shaft 20 is loosely mounted in the lower member of the frame 16, and has a gear wheel 21 fast to its lower end. The teeth of the gear wheels 8 and 21 75 are in mesh. The shaft 20 projects a short distance beyond the lower member of the frame 16 and engages the lower member of the frame 17 which is loosely mounted thereon.

A ratchet wheel 22 is secured to the 80 upper portion of the shaft 20 and bears against a boss on the lower member of the frame 17. A pawl 23 pivoted to the lower member of the frame 17 cooperates with the teeth of the ratchet wheel 22, whereby to 85 effect rotation of the frame 17 when the machine is in operation. A screw 24 passes loosely through the upper member of the frame 16 and engages a threaded opening in the upper member of the frame 17, and is provided with a hand wheel 25. A follower 26 is engaged by the lower end of the screw 24 and serves to clamp the container 15 when the same is placed in position to be cleaned.

The drum 15 or other form of container is 90 clamped between the follower 26 and the lower member of the frame 17, and rotates with said frame about the screw 24 and the shaft 20 as an axis. 95

It is observed that the ratchet 22 and pawl 100

23 admit of rotation of the frame 17 in one direction independently of the other parts to position said frame to admit of conveniently placing the drum or container 15 in position or to remove it from the machine after being cleaned. It is further observed that the container and its holder rotate about a diagonally disposed axis, while at the same time the container 15 and the frame 17 rotate about an axis coinciding with the shaft 20 and screw 24. The resultant gyratory movement gives a tumbling action to the container which is effective in cleaning the same as will be readily appreciated.

15 The provision of the pump 14 and the recess 5 enables the washing solution, if necessary, to be used repeatedly without wasting, and the discharge pipe of the pump is manipulated to deliver the solution over the 20 outer surface of the barrel or drum.

Having thus described the invention, I claim:

1. A drum washing machine comprising spaced shafts in longitudinal alinement, a 25 frame supported by the shafts at diagonally opposite points, a fixed gear wheel having one of said shafts passing loosely therethrough, a second frame journaled within the before mentioned frame and provided with 30 means for securing the drum to be cleaned, a shaft loosely mounted in both of said frames, a gear wheel fast to the last mentioned shaft and in mesh with the fixed gear wheel, and a ratchet and pawl connection between the last 35 mentioned shaft and the inner frame to admit of independent turning thereof for removing or placing the drum in position.

2. A drum washing machine comprising a base, standards rising from the base, alined 40 shafts mounted in the standards, an outer frame supported by and between the said shafts, and engaging the same at diagonally opposite points, a fixed gear wheel having one of the shafts passing loosely therethrough, 45 an inner frame, a shaft loosely engaging adjacent members of the inner and outer frame, a gear wheel secured to the last mentioned shaft and in mesh with the fixed gear wheel, a ratchet and pawl connection between the last 50 mentioned shaft and the inner frame, a screw passing loosely through the outer frame and engaging the adjacent member of the inner frame, and a follower adapted to be engaged by the inner end of said screw for clamping 55 the drum to be cleaned.

3. A drum washing machine comprising a supporting structure, an outer frame mounted on said structure for rotation about a diagonal axis, an inner frame having a longitudinal axis in common with the longitudinal axis of the outer frame, means carried by the supporting structure for rotating the outer frame about the diagonal axis, a shaft loosely engaged in adjacent ends of the two frames 60 on the longitudinal axes thereof, a gear on 65

said shaft, an element on the supporting structure engaged by said gear whereby said gear and shaft will be rotated when the frames turn about the diagonal axis, and a pawl and ratchet connection between the shaft and the inner frame whereby the inner frame may rotate with said shaft or may rotate independently to permit a drum to be removed or placed in position.

In testimony whereof I affix my signature. 75
